TILL DRAWER CONSTRUCTION

Joseph R. Showers, Sr., Shelbyville, Ind.

Application March 20, 1941, Serial No. 384,388

17 Claims. (Cl. 133—11)

This invention relates to cash drawers.

Cash drawers, preferably, are of wood construction because of certain advantages over metal drawers. In either case the drawers must be made to very close dimensions and must retain such dimensions in use for proper drawer operation.

Wooden cash drawers are, however, subject to variation due to weather and atmospheric conditions. Metal drawers are less subject thereto. However, in spite of this advantage, the popularity of the wooden drawer far exceeds that of the metal drawer.

It has been determined that the till forming compartment surface, if the length of the wood grain runs across the compartment from side to side, rapidly wears away at the softer portions leaving the surface rough and uneven. If the grain runs from front to rear, this condition is eliminated but the upper portion of the surface becomes rough, etc., which is objectionable.

Accordingly, laminated structures with the grain in the bottom portion running from front to back and with the grain running at right angles thereto in the upper portions is preferred.

However, wood when exposed to moisture elongates in a direction across the grain for the fibres thicken, swell or expand so that the aforesaid highly desirable laminated structure is objectionable to this extent because, as stated, drawers must be constructed to very exact dimensions and after construction must very closely retain the original dimensions regardless of weather or atmospheric conditions.

The problem, therefore, of producing a completely satisfactory cash drawer of wood type is one of utilizing the laminated structures and automatically compensating for the unavoidable expansion so that the original dimensions of the drawer always will be retained.

This constitutes the chief object of the invention.

This problem is solved by the present invention by utilizing compensating partitions and rigidly connecting the several laminated till compartment forming portions together by positive means in addition to glue.

The foregoing constitutes the chief feature of the invention.

Other objects and features of the invention will be set forth more fully hereinafter.

The full nature of the invention will be understood from the accompanying drawings, the following description and claims.

In the drawings,

Fig. 1 is a perspective view of a portion of till drawer structure embodying the invention.

Fig. 2 is a top plan view of a modified form of till drawer structure.

Fig. 3 is a side elevation thereof.

Fig. 4 is an enlarged transverse section taken on line 4—4 of Fig. 1 and of one form of the invention.

Fig. 5 is a longitudinal sectional view illustrating in dotted lines a second modification of a wood partition element.

Fig. 6 is a similar view of a third modification of a wood partition element.

Fig. 7 is a transverse sectional view of a metallic form of partition and associated drawer parts.

Fig. 8 is a side-elevational sectional view of a laminated till structure with a dowel interlock.

Fig. 9 is a similar view of a laminated till structure with a tenon interlock.

Fig. 10 is a similar view of a laminated till structure with a tongue and groove interlock.

In Figs. 1 and 4 of the drawings, 10 indicates the front of a cash drawer; 11 a side member suitably reduced as at 11a and 11b and provided with a bottom member 12 and a rear member 13. Screws 14 and 15 suitably connect the interlocked adjacent ends of the front and side members and the back or rear and side members, respectively.

Extending across the drawer from side to side are a plurality of coin tills designated generally by the letter A. These may be of individual character or multiple character, both forms being illustrated, see Figs. 8 and 9, and Fig. 10, respectively, as representative of singular and multiple coin tills.

Extending from front to rear of the drawer and suitably interlocking associated therewith is a partition structure 16. Herein, overlying the partition as well as the rear wall of a cash drawer and suitably seated in the notch 11c in the side member and extending from side member to side member, is the cross member 17. This in effect is, so far as the broad description is concerned, a conventional cash drawer.

Referring to Figs. 2 and 3, it will be observed that 110 indicates a drawer front; AA indicates coin tills; 116 partitions therebetween in side by side relation; 111 the side of the drawer extended rearwardly as shown; 113 the rear of the drawer; 112 the bottom of the drawer and 117 the rear cross member. The elongated screws 114 and 115 secure the side members 111 to the drawer front and drawer back, respectively.

55 Suitably secured to the upper edge of the side

members 111, as at 118, are outwardly directed angle members 119 having the oppositely projecting flanges 120 for drawer support and guidance. It will be noted that the drawer front 110, see Fig. 2, conceals the forward portions of these flanged members.

Figs. 1 and 2, therefore, represent a complete wooden drawer or a wooden drawer provided with outwardly directed metallic flanges, each equipped with a plurality of coin till compartments formed by the side walls of the drawer and intervening partition means. It is understood that the coin tills are positioned forwardly in the drawer and the compartments rearwardly thereof are adapted to receive paper bills, memoranda and the like.

Reference will now be had more particularly to Figs. 8, 9 and 10. In Fig. 8 it will be observed that 21 indicates a base portion of a till structure and 22 indicates upper or ridge portion of the coin till; 23 the glue joint between the ridge and base portions; 24 an opening extending through the base portion, and 25 an opening registering therewith and extending into the ridge portion 22 from the cemented base portion; 26 a dowel member seated in the registering openings. It will be understood that each ridge portion 22 is provided with at least two dowel members and these, preferably, are positioned near the ends of the ridge members.

In Fig. 9 numerals of the 100 series indicate like or similar parts, for example, 121 indicates the base portion; 122 the ridge portion; 123 the cemented union therebetween; 124 a longitudinal groove extending across from side to side in the base portion; 125 a confronting similar groove in the bottom of the ridge portion and 126 a tenon that is seated in both confronting grooves.

Referring to Fig. 10, numerals of the 200 series indicate like or similar parts, thus: 221 indicates the base portion; 222 the ridge portion; 223, the glue joint; 224 an elongated groove extending across the base portion from side to side and adapted to receive and seat a tongue 226 integral with and projecting from the ridge portion.

Figs. 8, 9 and 10 illustrate three suitable arrangements for positively securing ridge and base portions of the coin tills together, in addition to an adhesive connection therebetween and such additional connections are of positive character. Comparing Figs. 8, and 9, with Fig. 10, it will be noted that the first two are of singular coin till disclosure, while the latter is of multiple coin till disclosure. It is, of course, to be understood that the locking arrangements shown in Figs. 8 and 9 can be employed in multiple coin till constructions and that the locking arrangement provided in Fig. 10 can be employed in singular coin till constructions. These coin till constructions generally are designated hereafter and in the claims as of laminated character.

Referring more particularly to Fig. 1 by way of example only, it will be noted, see also Fig. 4, that the direction of the grain of the base portion of the coin till arrangement extends from front to rear of the drawer while the direction of the grain in the ridge portion of the coin till structure extends from side to side or across the drawer. When wood of this character is subjected to moisture conditions, the fibres thereof swell laterally, rather than linearly. Consequently, it will be apparent that the ridge por-

tions swell from front to back and do not swell from side to side, reference being had to the position of the same in the drawer structure. The base portion of the laminated till arrangement does not swell from front to back, but does swell from side to side. This is of a considerable amount when moisture conditions are excessive.

Such moisture conditions arise in two ways. One is when the relative humidity of the atmosphere is very high. In that event the wood takes up moisture and expands. The other is when coins are moist due to being handled in snowy or rainy weather and the moisture therefrom is absorbed by the coin tills. In either event, the till structures expand as indicated.

As has been set forth initially herein, the laminated till structure has certain advantages that are most desirable, notwithstanding and despite the fact that the base structures of such laminated till arrangements do have the highly objectionable feature of expanding, when subjected to moisture, in the direction across the drawer, thereby tending to swell or push the sides of the drawer away from each other. This results in the drawer binding and quite frequently also results, due to repeated expansion and contraction, in the drawer joints becoming loose. As initially set forth herein, the drawer should maintain its overall dimensions at all times throughout its life, thereby preventing such binding and also preventing the separation of the drawer components.

The screws maintain the sides of the drawer rigid with the front and back but the intermediate portion of the sides may be bowed outwardly by reason of till base expansion or elongation. The partition means indicated at 16 is utilized, therefore, in the present invention to compensate for this till compartment expansion or enlargement.

In Fig. 4 the partition 16 is shown provided with an upwardly directed groove 30. This groove 30 extends above the base portion of the till. Thus there are provided two adjacent side portions 31 which can be compressed towards each other in the expansion of the till base portions. If desired, this groove 30 may be packed or provided with a resilient material 32 which may be of asbestos sheet material, sponge rubber, cork sheet material or the like, whichever is found most desirable.

In Fig. 5 the groove 230 of the partition 216 is shown as not being coextensive with the partition, but terminates at 230a as shown. This means that the partition adjacent the paper receiving compartments of the cash drawer is not reduced or grooved.

In Fig. 6 a modified form of the invention is illustrated. In this form, the partition 316 is provided with the groove arrangement 330, but the same herein is of irregular upper surface outline, as indicated at 330a. It will be observed that the upper surface of the groove 330 always is positioned above the base portion of the laminated till arrangement so that the flexibility of the two adjacent side portions forming the groove in the partition means is ample to accommodate coin till base enlargement. Since the ridge portions of the coin tills do not elongate or enlarge across the drawer, flexibility is not required in the partition above the base structure unless it is found expedient to incorporate the same.

The partition shown in Figs. 4, 5 and 6 are of wood and the advantage of that shown in Fig. 5 over that shown in Fig. 4 is that the groove 230

terminates at 230a in Fig. 5. The advantage of the partition structure shown in Fig. 6 is that should an unusual degree of elongation occur in the coin till base structures and should the grain be uniform in the partition and extend longitudinally thereof, one of the side portions might fracture at the root of the groove. With the root of the top of the groove 330a being formed as shown, it is quite apparent that the tendency to fracture will be minimized because the groove is not provided with a continuous upper surface or root but said surface is of interrupted or serrated character and may follow generally the contour of the surface of the laminated till structure or may be as shown in Fig. 6.

Reference will now be had to Fig. 7 wherein numerals of the 400 series indicate like or similar parts. In this form of the invention, 421 indicates the base portion of the laminated till construction; 422 indicates the ridge portion of two spaced constructions. 416 indicates a metallic U-shaped partition formed by a single sheet of metal bent upon itself as shown. The groove 430 therein and between the side portions 431 may, if desired, be filled completely or partially with a cushioning material such as previously described, and herein the same is indicated by the numeral 432.

The resulting construction, therefore, is a drawer arrangement utilizing laminated wood coin till arrangements of the character indicated and providing partition means therebetween having a flexible arrangement provided at least in the base portion thereof for the accommodation of laminated coin till base enlargement incident to moisture and atmospheric changes.

While the invention has been illustrated and described in great detail in the foregoing description, the same is to be considered as illustrative and not restrictive in character.

The several modifications described herein, as well as others which will readily suggest themselves to persons skilled in this art, are all considered to be within the broad scope of the invention, reference being had to the appended claims.

The invention claimed is:

1. A till drawer structure including two spaced side walls, a plurality of till compartments therebetween and formed of separate pieces of material subject to swelling in the direction toward said walls, and till compartment side wall forming partition means between the pieces, and contacted thereby, the contacted portion of said partition means being compressible by the swellable material to prevent drawer side wall spreading and expansible to its former thickness when said swelling disappears.

2. A till drawer structure including two spaced side walls, a plurality of till compartments therebetween and formed of separate pieces of material subject to swelling in the direction towards said walls, and till compartment forming means between the pieces and contacted thereby, the contacted portion of said partition means being compressible by the swellable material to prevent drawer side wall spreading, and expansible to its former thickness when said swelling disappears, characterized by the partition means including an inverted, generally U-shaped sectioned member.

3. A till drawer structure including two spaced side walls, a plurality of till compartments therebetween and formed of separate pieces of mate-

rial subject to swelling in the direction towards said walls, and till compartment forming means between the pieces and contacted thereby, the contacted portion of said partition means being compressible by the swellable material to prevent drawer side wall spreading, and expansible to its former thickness when said swelling disappears, characterized by the partition means including an inverted, generally U-shaped sectioned member, and compressible means of solid type between the spaced portions of the U-shaped member.

4. A till drawer structure including two spaced side walls, a plurality of till compartments therebetween and formed of separate pieces of material subject to swelling in the direction towards said walls, and till compartment forming means between the pieces and contacted thereby, the contacted portion of said partition means being compressible by the swellable material to prevent drawer side wall spreading, and expansible to its former thickness when said swelling disappears, characterized by the partition means including an inverted, generally U-shaped sectioned member forming an elongated bottom opening groove, the length of the groove being at least coextensive with the length of the till compartments from front to rear of the drawer, the root of the groove, longitudinally being of serrated character, the greatest depths corresponding with the greatest depth of transverse swellable material in the compartment and all groove depths being greater than the immediate adjacent depths of the swellable material.

5. A till drawer structure including two spaced side walls, a plurality of till compartments therebetween and formed of separate pieces of material subject to swelling in the direction towards said walls, and till compartment forming means between the pieces and contacted thereby, the contacted portion of said partition means being compressible by the swellable material to prevent drawer side wall spreading, and expansible to its former thickness when said swelling disappears, characterized by the till compartment forming means including a base portion, and front and rear wall forming portions rigid therewith, said portions being of wood with the grain of wood in the base portion extending from front to rear and the grain in the front and rear wall portions extending substantially transverse thereto.

6. A till drawer structure including two spaced side walls, a plurality of till compartments therebetween and formed of separate pieces of material subject to swelling in the direction towards said walls, and till compartment forming means between the pieces and contacted thereby, the contacted portion of said partition means being compressible by the swellable material to prevent drawer side wall spreading, and expansible to its former thickness when said swelling disappears, characterized by the till compartment forming means including a base portion, and front and rear wall forming portions rigid therewith, said portions being of wood with the grain of wood in the base portion extending from front to rear and the grain in the front and rear wall portions extending substantially transverse thereto, the partition means including an inverted U-shaped sectioned member, the depth of division therein being at least equal to the greatest depth of the base portion.

7. A till drawer structure including two spaced

side walls, a plurality of till compartments therebetween and formed of separate pieces of material subject to swelling in the direction towards said walls, and till compartment forming means between the pieces and contacted thereby, the contacted portion of said partition means being compressible by the swellable material to prevent drawer side wall spreading, and expansible to its former thickness when said swelling disappears, characterized by the till compartment forming means including a base portion, and front and rear wall forming portions rigid therewith, said portions being of wood with the grain of wood in the base portion extending from front to rear and the grain in the front and rear wall portions extending substantially transverse thereto, and compressible means between the spaced portions of the U-shaped member.

8. A till drawer structure including two spaced side walls, a plurality of till compartments therebetween and formed of separate pieces of material subject to swelling in the direction towards said walls, and till compartment forming means between the pieces and contacted thereby, the contacted portion of said partition means being compressible by the swellable material to prevent drawer side wall spreading, and expansible to its former thickness when said swelling disappears, characterized by the till compartment forming means including a base portion, and front and rear wall forming portions rigid therewith, said portions being of wood with the grain of wood in the base portion extending from front to rear and the grain in the front and rear wall portions extending substantially transverse thereto, and means seated in one portion and extending into the adjacent portion for preventing separation therebetween, said means being of tongue type.

9. A till drawer structure including two spaced side walls, a plurality of till compartments therebetween and formed of separate pieces of material subject to swelling in the direction towards said walls, and till compartment forming means between the pieces and contacted thereby, the contacted portion of said partition means being compressible by the swellable material to prevent drawer side wall spreading, and expansible to its former thickness when said swelling disappears, characterized by the till compartment forming means including a base portion, and front and rear wall forming portions rigid therewith, said portions being of wood with the grain of wood in the base portion extending from front to rear and the grain in the front and rear wall portions extending substantially transverse thereto, and means seated in one portion and extending into the adjacent portion for preventing separation therebetween, said means being of dowel type.

10. A till drawer structure including two spaced side walls, a plurality of till compartments therebetween and formed of separate pieces of material subject to swelling in the direction towards said walls, and till compartment forming means between the pieces and contacted thereby, the contacted portion of said partition means being compressible by the swellable material to prevent drawer side wall spreading, and expansible to its former thickness when said swelling disappears, characterized by the till compartment forming means including a base portion, and front and rear wall forming portions rigid therewith, said portions being of wood with the grain of wood in the base portion extending from front

to rear and the grain in the front and rear wall portions extending substantially transverse thereto, and means seated in one portion and extending into the adjacent portion for preventing separation therebetween, said means being of tenon type.

11. A till drawer structure including two spaced side walls, a plurality of till compartments therebetween and formed of separate pieces of material subject to swelling in the direction towards said walls, and till compartment forming means between the pieces and contacted thereby, the contacted portion of said partition means being compressible by the swellable material to prevent drawer side wall spreading, and expansible to its former thickness when said swelling disappears, characterized by the till compartment forming means including a base portion, and front and rear wall forming portions rigid therewith, said portions being of wood with the grain of wood in the base portion extending from front to rear and the grain in the front and rear wall portions extending substantially transverse thereto, and means seated in one portion and extending into the adjacent portion for preventing separation therebetween, said means being of tongue type.

12. A till drawer structure including two spaced side walls, a plurality of till compartments therebetween and formed of separate pieces of material subject to swelling in the direction towards said walls, and till compartment forming means between the pieces and contacted thereby, the contacted portion of said partition means being compressible by the swellable material to prevent drawer side wall spreading, and expansible to its former thickness when said swelling disappears, characterized by the till compartment forming means including a base portion, and front and rear wall forming portions rigid therewith, said portions being of wood with the grain of wood in the base portion extending from front to rear and the grain in the front and rear wall portions extending substantially transverse thereto, and means seated in the base portion and extending into the front and rear wall portions for preventing separation therebetween, the partition means including an inverted U-shaped sectioned member, the depth of division therein being at least equal to the greatest depth of the base portion.

13. A till drawer structure including two spaced side walls, a plurality of till compartments therebetween and formed of separate pieces of material subject to swelling in the direction toward said walls, and till compartments side wall forming partition means between the pieces, and contacted thereby, the contacted portion of said partition means being compressible by the swellable material to prevent drawer side wall spreading and expansible to its former thickness when said swelling disappears, the till compartment forming means including a base portion, and front and rear wall forming portions rigid therewith, said portions being of wood with the grain of wood in the base portion extending from front to rear and the grain in the front and rear wall portions extending substantially transverse thereto, and means seated in the base portion and extending into the front and rear wall portions for preventing separation therebetween, the partition means including an inverted U-shaped sectioned member, the depth of division therein being at least equal to the

greatest depth of the base portion, and compressible means between the spaced portions of the U-shaped member.

14. In a compartmented till drawer structure comprising two spaced side walls, a front wall, a back wall, a bottom and partition means, the means and walls having their grain direction running longitudinally or lengthwise of each, the combination of unitary till compartment forming means arranged in side by side relation with said compartment forming means comprising a base portion superposed upon the bottom, said portion being of wood with the grain direction of said portion extending from front to back, and front and rear wall forming portions, said last mentioned portions each being of wood, the direction of the grain therein extending substantially transverse to the grain direction of the base portion, and means secured to one of said first and second mentioned portions and ex-

tending into the other of said portions, the base portion being exposed between the front and rear wall portions, the adjacent surfaces of said front and rear wall portions being inclined inwardly and downwardly, the exposed portion of the base portion being recessed and merging with said adjacent surfaces at opposite ends to form a smooth concave outlined cross-section till compartment with a coin engageable surface having the grain direction of certain portions thereof extending transversely of each other.

15. A till compartment forming means as defined by claim 14 wherein the last mentioned securing means is of dowel type.

16. A till compartment forming means as defined by claim 14 wherein the last mentioned securing means is of tenon type.

17. A till compartment forming means as defined by claim 14 wherein the last mentioned securing means is of tongue type.

JOSEPH R. SHOWERS, SR.
